UNITED STATES PATENT OFFICE

GEORGE HENRY ELWELL, OF NEW HAVEN, CONNECTICUT, ASSIGNOR TO THE GREEST MANUFACTURING COMPANY, OF NEW HAVEN, CONNECTICUT, A CORPORATION OF CONNECTICUT

ELECTRIC SWITCH

Application filed October 10, 1927. Serial No. 225,197.

The invention relates to improvements in electric switches and especially to that type of reciprocating switches operatively thrown by means of push elements. The applicant is 5 aware that the art discloses a swinging or oscillating contact making and breaking lever having a sliding pivotal mounting upon a coiled spring resting upon a fixed supporting base and having a bearing at its opposite end 10 adapted to ride upon the peaked cam of a reciprocating operating member, the oscillating switch lever being maintained in engagement with the peaked cam by the spring which supplies sufficient tension to cause the 15 lever to snap over the peak of the cam as the reciprocating member is operated in opposite directions. By a previous application the applicant has disclosed an oscillating contact making and breaking member carried by 20 the reciprocating operating member. In this application, however, there is disclosed the novel association of contacts mounted fixedly upon the supporting base and presenting themselves resiliently to a peaked cam member 25 slidingly mounted upon and carried by a reciprocating operating member. The objects therefore of the invention are to provide an electric switch of simple and economical construction; to provide an electric switch all 30 parts of which are mounted in a common transverse cavity in the supporting base; and to provide an electric switch involving such other features of the invention as may herein appear.

35 The following is the description of an embodiment of the invention, the construction of which within the scope of what hereinafter is claimed may be varied without departing from the spirit or modifying any of the advantages of the invention. Reference being had to the accompanying drawings (one sheet) the Figure 1 is an upright elevation, partly in cross-section, of an electric lamp socket without a casing but provided with the 40 improved switch; Figure 2 is an upright exterior elevation of the same lamp socket, but in a different position and with push element removed to illustrate the reciprocating members in cross-section; Figure 3 is a top view 45 of the base of a lamp socket supporting the

reciprocating operating member; and Figure 4 is a top view of the supporting base.

Referring more particularly to the drawings in which similar parts are similarly numbered the electric switch, while adapted for 55 associated with any electrical device requiring a switch, is illustrated here in connection with an electric lamp socket in which the supporting base is the body of insulation 1 having the transverse cavity 2 within which are 60 the pairs of spaced abutments 3 and 4 and the floor groove 5 communicating with the peripheral groove 6, as best illustrated by Figures 1 and 4. The reciprocating operating member comprises the cylindrical metal rod 7 having fixed at one extremity the push element 8 of black insulation material and at the other extremity the push element 9 assembled thereon by means of interengaging 65 screw-threads with which the extremity and the push element are each provided. Slidably mounted upon the metal rod 7 is the cylindrical cam member having the metallic grooved portion 10 and the grooved portion 70 of insulation material 11, the groove in each portion being endless and thus extending entirely around the cylindrical cam member so that between the two grooves there is formed the annular peaked cam 12. Coiled springs 75 13 of substantially equal tension are mounted upon and carried by the rod 7, one between the fixed push element 8 and the portion of insulation 11 of the sliding cam member, and the other between the screwed-on push element 9 and the metallic portion 10 of the sliding cam member, as best illustrated by Figures 1 and 3. The association of the reciprocating operating member, thus carrying the parts mounted thereon, with the body of insulation 1 is such that the movement of the 80 sliding cam member, comprised of the portions 10 and 11, is confined to the central part of the transverse cavity 2 between the abutments 3 and 4, while the reciprocating movement of the operating member is limited by the engagement of each inner end of the push elements 8 and 9 with the outer surfaces of the abutments 4 and 3, respectively, as best illustrated by Figure 3. Within the floor groove 5 is mounted the resilient contact 14 85 90 95 100

fixed to the body 1 within the peripheral groove 6 by means of a screw and therein serving as the binding-post 15. The contact 14 is provided with peaked portion of more or less 5 resiliency and adapted to engage the annular groove of either of the metallic or insulation material cam portions 10 or 11. Fixedly mounted to the washer 16, of insulation material, is a resilient peaked loop contact 17 also 10 adapted to engage the same annular groove of the portions 10 and 11 as engaged by the resilient contact 14, but diametrically opposite thereto, as illustrated by Figures 1 and 2. A convenient means of mounting this contact 15 17 upon the washer 16 is by securing the same thereto by the eyelet commonly employed to secure the center lamp-contact to the opposite side of the washer. The screw-shell binding-post may be provided in any desired way, 20 but it is illustrated as an integral arm of the screw-shell providing the binding-post 18 in a manner best illustrated by Figure 2 and made the subject of a previous application by the applicant.

25 From the foregoing description it obviously will be understood that, assuming the position of the movable parts to be the same as illustrated by Figure 1, by pushing the black push element 8 inwardly the adjacent coiled 30 spring will be compressed against the insulation portion 11 of the sliding cam member, the cam member being held against a yielding sliding movement by the resilient contacts 14 and 17. A predetermined number of coils 35 in the spring providing an absolutely closed spring before the inner end of the push element 8 engages the abutments 4 so that a complete operation of the push element 8 will thrust the compact spring against the sliding 40 cam member sufficiently to effect a dislodgment of both contacts 14 and 17 from within the groove in the metallic portion 10 of the sliding cam so that as the annular peak of the cam is pushed between the contacts 14 45 and 17 the release or the compressed spring quickly advances the cam member to engage the contacts 14 and 17 with the groove of the insulation portion 11 of the sliding cam member. Until the contacts 14 and 17 are fully 50 dislodged, as above described, the electrical connection remains closed as the contacts 14 and 17 are made, as it were, to climb to the annular peak 12, but upon the passing of the peak thereunder the opening of the circuit 55 is suddenly accomplished as the contacts 14 and 17 lodge within the annular groove of the insulation portion 11 of the sliding cam, the released spring having thrown the sliding cam member into position therefor. Operating 60 the red push element 9 in a similar manner a reversed action is had to lodge the contacts 14 and 17 within the annular groove of the metallic portion 10 of the sliding cam member to close the circuit. In assembling 65 the socket within a unitary casing (not illus-

trated) wherein oppositely positioned perforations are provided for the occupancy and operation of the push elements, the push element 9 being unscrewed and the rod 7 being withdrawn, freeing the coiled springs, the 70 remaining assembled parts of the socket are placed within the unitary casing and the rod 7 with a spring mounted thereon is held with its free end passed endwise into the casing 75 perforation, through the center passage of the sliding cam member to be presented upon the opposite end of the transverse cavity 2 within reach through the opposite perforation in the casing to enable the placing of the other coiled spring and screwing the red push element 80 upon the rod extremity.

What I claim is:—

1. An electric switch comprising a supporting base having a transverse passage partially intercepted by spaced abutments therein, and a reciprocating operating member mounted within the passage and carrying a relatively sliding spring-pressed peaked cam movable between the abutments and adapted by means of the operating member to be reciprocally spring-pressed into and out of electrical engagement with a fixed contact mounted upon the base. 90

2. An electric switch comprising a supporting base having a transverse passage partially 95 intercepted by spaced abutments therein, and a reciprocating operating member mounted within the passage and carrying between coiled springs a relatively sliding annular peaked cam movable thereon between the abutments and adapted by means of the operating member to be reciprocally spring-pressed into and out of electrical engagement with a fixed contact mounted upon the base. 100

3. An electric switch comprising a supporting base having a transverse passage partially 105 intercepted by spaced abutments therein, and a reciprocating operating member mounted within the passage and carrying between coiled springs of substantially equal tension 110 a relatively sliding member movable thereon between the abutments and having annular grooves of metallic and insulation material construction, respectively, so spaced as to form between them an annular peaked cam, the sliding member, upon the reciprocating movements of the operating member, being adapted to be spring-pressed into and out of electrical engagement with a fixed contact 115 mounted upon the base as the peak passes the contact to lodge the contact alternately in the grooves. 120

4. An electric switch comprising a supporting base having a transverse passage partially 125 intercepted by spaced abutments therein, and a reciprocating operating member mounted within the passage and carrying between coiled springs of substantially equal tension a relatively sliding member movable thereon between the abutments and having annular 130

grooves of metallic and insulation material construction, respectively, so spaced as to form between them an annular peaked cam and each adapted for alternate engagement with a resilient electrical contact provided by the base, the contact retarding the movement of the sliding cam until the full tensioning of a spring upon the operation of the reciprocating member.
